UNITED STATES PATENT OFFICE.

CARL G. SWENSON, OF INDIANAPOLIS, INDIANA, ASSIGNOR TO THE OAKES COMPANY,
OF INDIANAPOLIS, INDIANA, A CORPORATION OF INDIANA.

DESIGN FOR A FAN-BLADE ASSEMBLY.

52,762.

Specification for Design.

Patented Dec. 10, 1918.

Application filed February 28, 1918. Serial No. 219,703. Term of patent 14 years.

To all whom it may concern:

Be it known that I, CARL G. SWENSON, a citizen of the United States, residing at Indianapolis, in the county of Marion and State of Indiana, have invented a new, original, and ornamental Design for Fan-Blade Assemblies, of which the following is a specification, reference being had to the accompanying drawing, forming part hereof.

In such drawing, Figure 1 is a rear elevation of a fan blade assembly showing my

new design; and Fig. 2 is an edge or plan view of such fan blade assembly.

I claim:

The ornamental design for a fan blade assembly, as shown.

In witness whereof, I have hereunto set my hand at Indianapolis, Indiana, this 26th day of February, A. D. one thousand nine hundred and eighteen.

CARL G. SWENSON.
